MOISTENING DEVICE FOR TAPE-SERVING MECHANISMS

Alfred P. Krueger, Stratford, Conn., assignor to
Derby Sealers, Incorporated, Derby, Conn., a
corporation of Connecticut

Application July 26, 1945, Serial No. 607,222

2 Claims. (Cl. 91—38)

1

This invention relates to moistening devices for tape-serving mechanisms, and more particularly to a tape-dispensing machine of the type employing a receptacle for the moistening fluid, such as water, and a moistening element such as a brush or felt wick, for example, in which the moisture rises from the receptacle by capillary action.

In devices of this character, it is common to provide a fountain supply for the liquid in the receptacle, and the amount of moisture delivered to the tape is determined by the level of the water in the receptacle. That is, the higher the level of water, the shorter will be the travel to the upper edge of the moistening element in contact with the tape, and the greater will be the moistening effect. When the water level in the receptacle is fairly low, there is a considerable lag in the rising of the water from the level in the receptacle to the top of the brush. Under these circumstances, the tape at the beginning of the operation receives a considerable amount of moisture, sometimes an excess in amount, due to the fact that as the machine has been at rest the top of the brush is full of water. However, owing to the lag or the time required for the water to rise to the top of the moistening element, the remainder of the tape will not receive as great an amount, and possibly not enough, especially if the strip of tape is dispensed with speed. In other words, the water or moistening liquid does not rise by capillary action as fast as it is drawn from the top of the tape. It is, therefore, impossible to moisten the tape evenly and correctly by the sole control of the height of the level in the receptacle.

Also it is not uncommon for tape-dispensing devices which employ a capillary moistening element such as a brush to be provided with a pressure plate overlying the brush and exerting pressure thereon. The tape is fed between the brush and the pressure plate, and the pressure exerted by the latter may be adjusted, which will regulate the amount of moisture received by the tape from the brush. This method of regulation of the moisture received by the tape also has its disadvantages, particularly in the case of thin or light tape. In such machines the feed rollers are usually positioned rearwardly of the moistening element, and hence serve to push the tape over the brush and below the pressure plate. If the tape is relatively light and the pressure relatively heavy, the resistance to the passage of the tape between the brush and the pressure plate will be sufficiently great to cause the tape to

buckle instead of passing smoothly through the machine.

In the present device, it is contemplated to maintain a relatively high level of the water in the receptacle, and to maintain this level constant, so that the travel from this level to the top of the moistening element will be relatively short, and to maintain any desired pressure of the pressure plate on the brush for proper moistening and feeding of the tape, and to provide other means, that is, means other than adjustment of the level of the water in the receptacle, or adjustment of the pressure plate, for regulating the amount of moisture delivered to the tape. By such an arrangement, the tape will always receive the proper amount of moisture, and, as there will be a relatively short distance for the water to rise under capillary action, it will be supplied to the tape as fast as it is used, and thus the tape will be moistened evenly throughout the length of the strip which is dispensed. The amount of water delivered to the tape may be regulated as shown herein by effecting transverse pressure upon the brush or other moistening element so as to, in effect, reduce the capillary area, by squeezing together the elements of the moistening element so that there will be less space between them for the travel of the water.

One object of the present invention is to provide a new and improved moistening device for tape-dispensing machines.

Another object of the invention is to provide a tape-dispensing machine having means for moistening a gummed tape, such that the moisture will be supplied evenly to the gummed surface of the tape and in the proper quantity.

A still further object of the invention is to provide means for applying moisture to the gummed surface of a strip of tape by means of a moistening element in which the liquid rises by capillary action, the amount of moisture being regulated by adjusting the area of capillary passages by applying transverse pressure upon the moistening element.

Still another object of the invention is to provide a tape-dispensing machine having a liquid receptacle and a moistening element disposed in the receptacle and projecting therefrom, so that the gummed surface of the tape may be drawn thereover, and means for maintaining a constant level of liquid in the receptacle together with means for adjusting the rise of the liquid in the moistening element by capillary action, so as to regulate the quantity of moisture applied to the tape.

To these and other ends the invention consists in the novel features and combinations of parts to be hereinafter described and claimed.

In the accompanying drawings:

Fig. 1 is a side elevational view of a tape-dispensing machine embodying my invention;

Fig. 2 is a sectional view of the front portion of the machine, showing the liquid receptacle and moistening element and cooperating parts;

Fig. 3 is a top elevational view of the liquid receptacle removed from the machine;

Fig. 4 is a view similar to Fig. 2, showing another adjustment of the parts; and

Fig. 5 is a view similar to Fig. 4, showing a modified form of my device.

For purposes of illustration, I have shown a tape-dispensing device comprising a body or frame 10 having at its forward portion supporting means 11 for a liquid receptacle 12. As shown in Fig. 1, this liquid receptacle may be connected by a tube 13 to a fountain device 14 in which stands in inverted position a water container such as a bottle 15. It will be understood that the level of liquid in the receptacle 12 is controlled by the height of that in the fountain 14 and, with the bottle discharging into this member, the liquid in the receptacle 12 will be maintained at a constant level so long as there is any supply within the bottle. Preferably, as will be hereinafter explained, the fountain 14 is so positioned that the level of liquid in the receptacle will be maintained close to the top thereof.

As the tape issues from the machine, it is designed to be fed past a knife 17 and between a lower guide plate 18 and an upper pressure plate 19, the latter being resiliently urged toward the plate 18 by tension springs 20 (Fig. 1).

Supported in inverted position in the receptacle 12 is a moistening element, such, for example, as a brush 21, although the invention is not limited to this type of element. The bristles of the brush project through the upper open end of the receptacle 12, and the pressure plate 19 will be held against the upper ends of the bristles by the springs 20 (only one being shown), so that the tape will be properly pressed downwardly upon the moistening brush during its passage from the machine. It will also be apparent that the rear face of the brush lies against the forward edge of the guide plate 18.

Means are provided for pressing the brush against the forward edge of the guide plate and, therefore, compressing or squeezing the bristles together so as to adjust the effective area of the capillary passages in the brush and thereby adjust or regulate the flow of liquid by capillary action from that in the receptacle to the upper edge of the brush. As shown, this means comprises a cover plate 22 slidably mounted upon the upper edges of the walls of the receptacle, this plate having a cut-away portion 23 through which the brush projects. As shown, the plate is provided with slots 24 within which are disposed screws 25 secured to the receptacle, so that the plate 22 will be guided in its sliding adjustment upon the receptacle. Bowed springs 26 may bear against the head of the screws 25 and against the plate to hold the latter in position.

An adjusting screw 27 is threaded into the front wall of the receptacle and is provided adjacent its rear end with an enlarged portion 28 having therein an annular recess 29 designed to be loosely received within a slot 30 in a lug 31, depending from the plate 22. The latter may also be provided with an upstanding rib or bead

32 adjacent the edge of the cut-away portion 23 to bear against the brush or other moistening element and compress the latter against the plate 18. It will be apparent that adjustment of the screw 27 moves the plate 22 to and from the brush 21 as permitted by the slots 24, so that the brush may be compressed to a greater or less degree against the plate 18 or may be left free and loose as desired.

As has been stated, it is contemplated that the water or moistening liquid within the receptacle 12 will be kept at a constant level and at a relatively high level, so that only a short travel of the water will be necessary to carry it to the upper edge of the brush which contacts the tape. This will enable the moistening liquid to travel to the upper end of the brush, as it is removed therefrom by passage of the tape thereover without excessive lag, and the amount of water passing upwardly through the brush may be regulated by the pressure exerted on the brush by the plate 22.

As shown in Fig. 4, the adjusting plate or cover plate 22 has been withdrawn to the left until there is little or no pressure upon the bristles of the brush. They, therefore, stand in a normal relatively free position, spread apart to some extent, so that there is a considerable area between them for the moistening liquid. This position of the parts results in the passage of a maximum amount of the liquid to the upper edge of the brush and, therefore, to the tape. If it is desired, however, to decrease the amount of moisture applied to the tape, the adjusting screw 27 is rotated in the direction to advance the plate 22 against the brush to the position shown in Fig. 2, where it will be noted the bristles are compressed between the bead 32 and the forward edge of the plate 18. The result of this transverse pressure upon the brush will be a lessening of the effective area of the capillary passages therein and, therefore, a lessening of the amount of moisture flowing to the edge of the brush and, therefore, of the amount applied to the tape. The amount of moisture applied to the tape may thus be readily and conveniently adjusted, so that its gummed surface will always be properly moistened, while the maintenance of the liquid in the receptacle at a high constant level will eliminate excessive lag between the using-up of moisture by the tape and the delivery thereof to the upper edge of the brush.

In Fig. 5 of the drawing, I have shown a somewhat modified form of my invention. In this instance, the pressure plate overlying the brush, such as the pressure plate 19 of Fig. 2, is omitted and the tape issues from the machine over a guide roll 35 and through a throat formed by an upper plate 36 and a lower guide plate 37 formed integrally with the receptacle 38. The plate 37 is provided with a forwardly extending portion 39 adapted to rest against the rear face of the brush 40 and cooperate with the bead 41 on the rear edge of the adjustable cover plate 42 to compress the brush and thereby vary its capillary capacity. It will be also understood that in this form of my invention, means will be provided for maintaining the liquid in the receptacle 38 at a constant level and that the cover plate 42 of the receptacle may be adjusted by the adjusting screw 43 as previously described in connection with the modification shown in Figs. 1 to 4.

It may also be observed that while the brush

21 shown in Figs. 2 and 4 is provided with a beveled or chiseled upper edge so as to better cooperate with the inclined lower surface of the pressure plate 19, the brush 40 may appropriately have a rounded upper end as shown in Fig. 5 as, in this device, it is contemplated that the tape shown at 44 will be drawn over the brush by the hand of the user. Adjustment of the cover plate 42 will effect transverse pressure upon the brush, squeezing the bristles together and thus adjust the amount of liquid passing from the receptacle to the top of the brush, so that the proper amount of moisture may be applied to the tape at all times.

While I have shown and described some preferred embodiments of my invention, it will be understood that it is not to be limited to all of the details shown, but is capable of modification and variation within the spirit of the invention and within the scope of the claims.

What I claim is:

1. A moistening device for a tape-dispensing machine comprising a liquid receptacle, a capillary moistening element supported in said receptacle and projecting therefrom in which element the moisture rises to the upper surface thereof, a plate covering the forward portion of the receptacle, said cover plate being mounted for slidable movement on the upper edges of the side walls of the receptacle, the rear edge of which plate is adapted to engage the front of the moistening element, an abutment at the rear side of the moistening element, a pressure plate urged toward the upper surface of the moistening element, and means for adjusting said cover plate toward the moistening element to transversely compress the latter between the rear edge of the cover plate and the abutment, said cover plate having an enlarged bead at its rear edge to bear against the moistening element, and means to guide said cover plate in its movement toward and away from the brush and to

5 restrain it against twisting movement in its own plane.

2. A moistening device for a tape-dispensing machine comprising a liquid receptacle, a capillary moistening element supported in said receptacle and projecting therefrom in which element the moisture rises to the upper surface thereof, a plate covering the forward portion of the receptacle, said cover plate being mounted for slidable movement on the upper edges of the side walls of the receptacle, the rear edge of which plate is adapted to engage the front of the moistening element, an abutment at the rear side of the moistening element, a pressure plate urged toward the upper surface of the moistening element, means for adjusting said cover plate toward the moistening element to transversely compress the latter between the rear edge of the cover plate and the abutment, means 15 for maintaining a constant level of liquid in the receptacle, and means to guide said cover plate in its movement toward and away from the brush and to restrain it against twisting movement in its own plane.
